[57] CLAIM

The ornamental design for an automatic tape cartridge selecting and playing mechanism, substantially as shown.

DESCRIPTION

FIG. 1 is a top plan view of an automatic tape cartridge selecting and playing mechanism, showing my new design;

FIG. 2 is a front elevational view of the mechanism shown in FIG. 1;

FIG. 3 is a side elevational view of the mechanism as seen from the right side of FIGS. 1 and 2;

FIG. 4 is a side elevational view of the mechanism as seen from the left side of FIGS. 1 and 2;

FIG. 5 is a rear elevational view of the mechanism; and

FIG. 6 is a bottom plan view of the mechanism.

*Fig. 1.**Fig. 2.**Fig. 3.**Fig. 4.**Fig. 5.**Fig. 6.*
